No. 36,692.

Patented December 22, 1903.

UNITED STATES PATENT OFFICE.

HANS HOHNER, OF NEW YORK, N. Y.

DESIGN FOR A HARMONICA.

SPECIFICATION forming part of Design No. 36,692, dated December 22, 1903.

Application filed October 17, 1903. Serial No. 177,600. Term of patent 7 years.

To all whom it may concern:

Be it known that I, HANS HOHNER, a citizen of Germany, residing at New York city, Manhattan, county and State of New York, have invented a new, original, and ornamental Design for Harmonicas, reference being had to the accompanying drawing, which represents a perspective view of a harmonica, showing my new design.

What I claim is—

The ornamental design for a harmonica, substantially as herein shown.

HANS HOHNER.
